CLAIM

The ornamental design for a textured glove and former therefor, as shown and described.

DESCRIPTION

FIG. 1 is a front, isometric view of a textured glove and former therefor showing my new design.

FIG. 2 is a front elevational view thereof.

FIG. 3 is a back elevational view thereof.

FIG. 4 is a left side elevational view thereof.

FIG. 5 is a right side elevational view thereof.

FIG. 6 is a top elevational view thereof.

FIG. 7 is a bottom elevational view thereof; and,

FIG. 8 is an enlarged view of the area designated **8** in FIG. 1.

The symbolic break lines (e.g., pairs of dash-dash broken lines) represent a boundary between claimed and unclaimed subject matter and form no part of the claimed design. The appearance of any portion of the article between the break lines forms no part of the claimed design.
